UNITED STATES PATENT OFFICE.

ARCHIE G. HOHENSTEIN, OF NEW HAVEN, CONNECTICUT.

STEAM-BOILER.

SPECIFICATION forming part of Letters Patent No. 759,525, dated May 10, 1904.

Application filed June 1, 1903. Renewed April 15, 1904. Serial No. 203,237. (No model.)

To all whom it may concern:

Be it known that I, ARCHIE GERRY HOHENSTEIN, a citizen of the United States, residing at New Haven, in the county of New Haven and State of Connecticut, have invented or discovered certain new and useful Improvements in Steam-Boilers, of which improvements the following is a specification.

The invention described herein relates to certain improvements in water-tube boilers, the improvements being more especially applicable for small boilers.

The invention has for its object a construction wherein the circulating system consists of two water-chambers formed by headers at the front of the boiler divided into two chambers which are connected by cross-tubes arranged in three series, one series feeding to two of the series, or vice versa, an elevated drum connected to the headers, downtakes at the ends of the drum adapted to support the same and connected by tubes forming water-walls to short sections of tubes connected in turn to an equalizing-box for the headers.

The invention is hereinafter more fully described and claimed.

In the accompanying drawings, forming a part of this specification, Figure 1 is a front elevation of my improved boiler, a portion of the casing being removed. Fig. 2 is a sectional elevation of the same; and Fig. 3 is an end elevation, the rear wall of the casing being broken away.

In the practice of my invention the headers are connected at the lower ends by a distributing or equalizing box 39, which is supported by water-legs 40 at its ends. The headers are divided transversely either by partition-diaphragm 4 or by forming them in two sections, as shown and described in application, Serial No. 159,684, filed June 1, 1903. The lower water-chambers or sections of headers are connected to the outer ends of a series of tubes 5, whose inner or rear ends are connected to junction-boxes 6. These junction-boxes are also connected to the rear ends of two series of tubes 7 and 8, having their front ends connected to the upper water-chambers or sections of headers above the diaphragm 4.

This arrangement of the tubes may be reversed, as shown and described in the application referred to. The upper water-chambers or ends of the headers are connected by cross-tubes 11 to the upper drum 12, which is supported by downtake-pipes 13 at each end. The lower ends of these downtake-pipes are connected by tubes 20 to the water-legs 40, said tubes so arranged and connected to the downtakes and water-legs that they will contact with each other and form practically tight water-walls for the sides of the furnace or fire-box. In this construction the circulation will be as follows: Starting from the water-legs and the equalizing-box 39 it will flow through the lower portions of the headers along the series of tubes 5, thence along both series of tubes 7 and 8 to the upper headers. From these headers the water will flow by the pipes 11 into the drum 12 and thence down through the downtakes along the water-walls to the water-legs and equalizing-box, completing the loop.

It will be observed that the tubular columns 13 will securely support the drum 12, to which the upper ends of the headers are tied by the tubes 11. The lower ends of the headers are secured to the equalizing-box, which is tied to the lower ends of the columnar downtakes by the water-walls. Within this rigid frame the series of tubes 5, 7, and 8 are free to expand and contract, their rear ends being merely supported on the rear wall of the fire-box.

I claim herein as my invention—

1. A water-tube boiler having in combination two water-chambers, three connected series of tubes extending from said chambers, a drum connected to the upper water-chamber, tubular columns forming downtakes and arranged under the ends of the drum, and connections from the downtakes to the lower water-chambers, substantially as set forth.

2. A water-tube boiler having in combination a distributing or equalizing box, lower water-chambers connected to said box, upper water-chambers, three connected series of tubes extending from the upper and lower water-chambers, a drum, tubular columns supporting said drum and serving as downtakes,

water-walls forming the sides of the fire-box and connected to the downtakes and distributing-box, substantially as set forth.

3. A water-tube boiler having in combination a distributing or equalizing box, water-legs supporting said box, headers connected to the box, three connected series of tubes extending from the headers, a drum, a series of tubes connecting the drum and headers, tubular columns supporting the drum and serving

as downtakes, and water-walls connecting the downtakes and water-legs, substantially as set forth.

In testimony whereof I have hereunto set my hand.

ARCHIE G. HOHENSTEIN.
